UNITED STATES PATENT OFFICE.

EMMETT F. CARTER, OF SCHENECTADY, NEW YORK, ASSIGNOR TO GENERAL ELECTRIC COMPANY, A CORPORATION OF NEW YORK.

HIGH-FREQUENCY SIGNALING SYSTEM.

Application filed January 14, 1927. Serial No. 181,189.

My invention relates to high frequency signaling systems, and particularly to signaling systems adapted for single frequency duplex operation.

5 In systems of this type the output of the transmitting circuit and the input of the receiving circuit are usually inductively associated so that during periods of transmission energy is supplied from the output of the transmitting circuit to the input of the receiving circuit, where it produces undesirable effects. Heretofore means have been provided for protecting the receiving circuit from these undesirable effects; such means 15 having included electron discharge devices in which the filament potential is controlled responsively to voice currents in the transmitting circuit, said electron discharge devices being adapted to render the receiving circuit insensitive during periods in which voice frequencies are impressed upon the transmitter. These means are unsatisfactory for several reasons but principally, due to their complex circuit structure, to the time 20 delay incident to their operation and to the large amount of energy absorbed from the audio channels of the transmitting circuit in energizing the filaments of these devices.

The purpose of my invention is to overcome these and other disadvantages of the prior circuits and to provide a protective device for the receiving circuit which is more simple in its circuit construction than those heretofore proposed, and which operates substantially simultaneously with the functioning of the transmitting circuit.

In my copending application, Serial No. 752,243, filed November 25, 1924, entitled "High frequency duplex signaling system" 40 I have shown an electron discharge device connected in shunt with the receiving circuit to protect it from energy received from the associated transmitter. In accordance with my present invention the desired result is 45 accomplished by controlling the discharge device or discharge devices, each of which comprises a normally inactive shunt to the receiving circuit in response to operation of the transmitter.

50 The novel features which I believe to be characteristic of my invention are set forth with particularity in the appended claims.

My invention itself, however, both as to its organization and method of operation will best be understood by reference to the following description taken in connection with the accompanying drawing, in which I have illustrated diagrammatically one form of my invention.

Referring to the drawings, 1 denotes a circuit leading to an antenna or to wire lines depending upon the particular application for which the system is employed, 2 indicates generally the receiving circuit, 3 indicates generally the transmitting circuit and 4 indicates the usual coupling transformer for connecting the input circuit of the receiver and the output circuit of the transmitter with the common antenna or wire line 1. 5 indicates the usual telephone circuit or voice channel leading to the operator's station and 6 indicates a coupling transformer for connecting the output circuit of the receiver and the input circuit of the transmitter with the voice channel 5. 7 indicates the usual net work circuit for balancing the three winding transformer 6. Since my invention is primarily concerned with the receiving circuit, only so much of the transmitting circuit as is necessary to an understanding of my invention is shown in the drawing. Hence the apparatus which is associated with the audio frequency channel of the transmitting circuit has been designated by the rectangle 9, and likewise the apparatus which is associated with the radio frequency channel has been designated by the rectangle 10. 11 indicates an electron discharge device which may be utilized as the generator of the radio frequency voltages employed during transmission and 12 indicates a second electron discharge device in the transmitting circuit for controlling the operation of the electron discharge device 11.

In the receiving circuit, 13 indicates an electron discharge device which may be employed as a detector. 14 indicates the input circuit to this detector which is supplied with energy through transformer 15; link circuit 16 and coupling transformer 4 from the antenna or wire line 1. For the purpose of tuning these circuits the variable condenser 17 has been provided in series with the link circuit 16 and the variable condenser 18 in

shunt with the input circuit 14. 19 and 20 indicate electron discharge devices which are connected in shunt relation with the input circuit 14 and the link circuit 16, respectively. 5 The cathode 21 of the electron discharge device 19 is connected through cathode conductors 30 to one side of the input circuit 14 at the point 22, and the anode 23 of the electron discharge device 19 is connected through 10 a suitable source of potential 24 to the opposite side of the input circuit 14. Likewise the cathode 25 of the electron discharge device 20 is connected to one side of the link circuit 16 at the point 26 and the anode 27 is connected through a suitable source of potential 28 to the opposite side of the link circuit 16. The cathodes 21 and 25, together with the cathode 29 of the detector 13, have been connected in parallel by the conductors 30 15 across a suitable source of potential 31, this arrangement being adopted as a matter of convenience and economy since any suitable means may be employed for energizing the cathode. The grid 32 of the electron discharge device 20 and the grid 33 of the electron discharge device 19 are connected together through conductors 34 and 35 and they are also connected through a suitable source of potential 36, resistance 37 and conductor 38 to the cathode conductors 30. One side of the resistance 37 is connected through conductor 38 to the negative side of a high voltage source 39 and to appropriate conductors in the audio channels of the transmitting apparatus 9. The opposite side of resistance 37 is connected through a conductor 40 to the cathode 41 of the electron discharge device 12 in the transmitting circuit. A bypass condenser 42 is connected across the 20 resistance 37 for the purpose of shunting alternating currents which may flow in the conductor 40 and conductor 38 out of the resistance 37. The cathode 41 of the electron discharge device 12 and the cathode 43 of the electron discharge device 11 are energized from a suitable source of energy 44 through cathode transformers 45, and cathode conductors 57 and 56 respectively. 25 46 represents the usual oscillatory circuit of the alternating current generator 11, having one extremity 47 connected to the anode 48 of the electron discharge device 11, and its opposite extremity 49 connected to the grid of the electron discharge device 11 and an intermediate point 50 connected to the cathode 43 and through the conductor 51 to the anode 52 of the electron discharge device 12. The anode 48 is provided with a suitable high potential from the high potential source 39 through the choke coil 53.

The operation of my device is as follows. During normal operation of the system, when the transmitting circuit is idle and reception is taking place through the receiving channel 65 2, the electron discharge devices 19 and 20

will be inactive. This is because a high negative potential is impressed upon the control elements 33 and 32 of these devices with respect to their cathodes 21 and 25 respectively by the source 36 through a circuit 70 as follows: cathode conductor 30, conductor 38, resistance 37, source of potential 36 and conductors 35 and 34. Hence no current will flow through the anode cathode circuit of these devices and they will have no effect 75 upon the system. Reception will, therefore, take place in the usual way.

Assume now that the operator speaks into the microphone at the operator's station. Voice frequencies will then be transmitted through the voice channel 5 coupling transformer 6 and audio apparatus 9, from which they will be impressed upon the grid 55 of the control electron discharge device 12, causing this grid to assume a positive potential with 80 respect to the cathode 41. This, in turn, decreases the resistance between the cathode 41 and anode 52 and thereby causes a direct current potential to appear between the cathode 43 and anode 48 of oscillation generator 11. 90 This being true radio frequency currents will be generated by the generator 11 and impressed upon the amplifying apparatus 10 in the usual way. Under this condition a direct current will flow from the source 39 through a circuit including the choke coil 53, anode 48, space between the anode 48 and the cathode 43 of the electron discharge device 11, cathode 43, cathode conductors 56, conductor 51, anode 52, space between the anode 52 and cathode 41 of electron discharge device 12, cathode 41, cathode conductors 57, conductor 40, resistance 37, conductor 38 to the negative side of the source 39. As a result 95 a potential will build up on resistance 37 which will have the polarity indicated in the drawing. This potential being in series relation with that of the source 36 in the grid circuits of the electron discharge devices 19 and 20 will overcome the potential of the 100 source 36 and cause the grids 33 and 32 to be impressed with a positive potential with respect to their respective cathodes. Current will then flow from one side of the link circuit 16 through the electron discharge device 11 to the opposite side of this circuit and likewise, current will flow from one side of the input circuit 14, through the electron discharge device 19 to the opposite side and these 105 devices will constitute comparatively low resistance shunts across their respective tuned circuits. This being the case, these circuits will be detuned and the transmission efficiency of the system will be diminished. Hence energy which may be fed from the output circuit 58 of the transmitting circuit 3 through the coupling transformer 4 into the link circuit 16 and the input circuit 14 of the receiving circuit will be transferred through this circuit so inefficiently that it will be re- 110 115 120 125 130

duced to such a degree as to produce no undesirable effects upon the receiving apparatus. When the operator stops speaking into the microphone at the operator's station the potential on resistance 37 will diminish and that of the source 36 will again become effective upon the grids 33 and 32 of the electron discharge devices 19 and 20 respectively, causing them to assume a negative potential. 10 Hence these electron discharge devices again become inoperative and reception will again take place in the normal manner.

While in the particular embodiment of my invention shown in the drawing I have shown 15 two electron discharge devices, it is to be understood that either of these may be omitted, in which case the other would serve to detune the circuit with which it is associated and acting through the transformer 15

20 would detune the other tuned circuits of the system. Likewise, it may be preferred to use only the one tuned circuit, in which case the input circuit 14 would be coupled directly to the coupling transformer 4.

25 Thus it will be apparent that I have provided a device which, among other advantages, is more simple in its circuit construction than those heretofore proposed, which operates substantially simultaneously with 30 the functioning of the transmitting circuit thereby substantially eliminating any undesirable effects resulting from time delay between the initiation of high frequency currents in the transmitting circuit and the application of the protective device to the 35 receiving circuit and which absorbs only a negligible amount of energy from the transmitting circuit.

While I have illustrated and described only 40 one embodiment of my invention, it will be obvious that my invention is by no means limited to the particular embodiment indicated, but that many modifications in the circuit arrangements and instrumentalities employed in carrying out my invention may be 45 made without departing from the scope thereof as set forth in the appended claims.

What I claim as new and desire to secure 50 by Letters Patent of the United States, is.—

50 1. In a signaling system employing both a transmitting circuit and a receiving circuit, means for protecting said receiving circuit from said transmitting circuit, said means comprising an electron discharge device having an anode, a cathode and a control element, said anode being associated with one side of said receiving circuit, said cathode being associated with the other side of said receiving circuit and a source of potential 55 which is variable responsively to the functioning of said transmitting circuit, said control element being associated with said source of potential.

60 2. In a signaling system employing both a transmitting circuit and a receiving circuit,

means for protecting said receiving circuit from said transmitting circuit, said means comprising an electron discharge device having an anode, a cathode and a control element, said anode being associated with one 70 side of said receiving circuit, said cathode being associated with the other side of said receiving circuit and a source of direct current potential which is variable responsively to the functioning of said transmitting circuit, said control element being associated with said source of potential.

75 3. In a signaling system employing a transmitting circuit and a receiving circuit, means for protecting said receiving circuit from 80 said transmitting circuit comprising a number of tuned circuits in said receiving circuit, an electron discharge device associated with each of said tuned circuits and having an anode, a cathode and a control element, each of said anodes being connected to one side of one of said tuned circuits, each of said cathodes being connected to the other side of the corresponding tuned circuits and means responsive to the functioning of said transmitting circuit for controlling the potential of 85 said control elements.

4. In a signaling system employing a transmitting circuit and a receiving circuit, means for protecting said receiving circuit from 90 said transmitting circuit comprising a number of tuned circuits in said receiving circuit, an electron discharge device associated with each of said tuned circuits and having an anode, a cathode and a control element, each of said anodes being connected to one side of one of said tuned circuits, each of said cathodes being connected to the other side of the corresponding tuned circuits and means comprising a source of direct current 95 potential which is variable responsively to the functioning of said transmitting circuit for controlling the potential of said control elements.

5. In a signaling system employing a transmitting circuit and a receiving circuit, means for protecting said receiving circuit from 100 said transmitting circuit comprising a number of tuned circuits in said receiving circuit, an electron discharge device associated with 105 each of said tuned circuits and having an anode, a cathode and a grid, each of said anodes being connected to one side of one of said tuned circuits and each of said cathodes being connected to the other side of the corresponding tuned circuits and means responsive to the functioning of said transmitting circuit for varying the potential on said 110 grids, said means comprising a resistance connected between said cathodes and said grids, 115 the current in said resistance being variable 120 responsively to the functioning of said transmitting circuit.

6. In a signaling system employing a 125 transmitting circuit and a receiving circuit,

- said receiving circuit including a number of tuned circuits, a protective device comprising an electron discharge device associated with each of said tuned circuits and having an anode, a cathode and a grid, each of said anodes being connected to one side of one of said tuned circuits and each of said cathodes being connected to the other side of the corresponding tuned circuits, an oscillation generator in said transmitting circuit having an anode circuit and means responsive to the current flowing in said anode circuit for controlling the potential on said grids.
7. In a signaling system employing a transmitting circuit and a receiving circuit, said receiving circuit including a number of tuned circuits, a protective device comprising an electron discharge device associated with each of said tuned circuits having an anode, a cathode and a grid, each of said anodes being connected to one side of one of said tuned circuits and each of said cathodes being connected to the other side of the corresponding tuned circuits, an oscillation generator in said transmitting circuit having an anode circuit, and a resistance connected in said anode circuit, said resistance being also connected between the grids and cathodes of said electron discharge devices.
8. In a signaling system employing a transmitting circuit and a receiving circuit, said receiving circuit including a plurality of associated tuned circuits, a protective device comprising an electron discharge device having an anode, a cathode and a grid, said anode being connected to one side of one of said tuned circuits and said cathode being connected to the other side of said tuned circuit, an oscillation generator in said transmitting circuit having an anode circuit and means responsive to the current flowing in said anode circuit for varying the potential on said grid.
9. In a signaling system employing a transmitting circuit and a receiving circuit, said receiving circuit including a plurality of associated tuned circuits, a protective device comprising an electron discharge device having an anode, a cathode and a grid, said anode being connected to one side of one of said tuned circuits and said cathode being connected to the other side of said tuned circuit, an oscillation generator in said transmitting circuit having an anode circuit and means responsive to the current flowing in said anode circuit for varying the potential on said grid, said means comprising a resistance connected in said anode circuit and between the cathode and grid of said electron discharge device.
10. In a signaling system employing a transmitting circuit and a receiving circuit, means for protecting said receiving circuit from said transmitting circuit comprising an electron discharge device having a cathode and an anode, said cathode being connected to one side of said receiving circuit, and said anode being associated with the other side of said receiving circuit, a vacuum tube oscillation generator in said transmitting circuit having an anode circuit, and means in said anode circuit for controlling the impedance between said first mentioned cathode and anode.
11. In a signaling system employing a transmitting circuit and a receiving circuit, means for protecting said receiving circuit from said transmitting circuit including a number of tuned circuits in said receiving circuit, an electron discharge device connected in shunt relation with each of said tuned circuits, a vacuum tube oscillation generator in said transmitting circuit having an anode circuit and means in said anode circuit for varying the impedance of said shunt connected electron discharge devices responsive to the functioning of said generator.
12. In a signal system employing a transmitting circuit and a receiving circuit, means for protecting said receiving circuit from said transmitting circuit comprising a plurality of associated tuned circuits in said receiving circuit, an electron discharge device connected in shunt relation with one of said tuned circuits, a vacuum tube oscillation generator in said transmitting circuit having an anode circuit and means in said anode circuit for controlling the impedance of said shunt connected electron discharge device.
13. In a high frequency signaling system employing a transmitting circuit and a receiving circuit, means for protecting said receiving circuit from interference from said transmitting circuit comprising a number of tuned circuits in said receiving circuit, an electron discharge device having a cathode, an anode and a control element associated with each of said tuned circuits, said anodes being associated with one side of said tuned circuits and said cathodes being associated with the opposite sides of the corresponding tuned circuits and means responsive to the functioning of the transmitting circuit for controlling said control elements.
14. The combination in a signaling system of a transmitting circuit including an electron discharge oscillation generator having an anode circuit, a receiving circuit, a normally inactive shunt for said receiving circuit and means responsive to current flowing in said anode circuit for controlling said normally inactive shunt.
15. The combination in a high frequency signaling system, a transmitting circuit including an electron discharge oscillation generator having an anode circuit, a receiving circuit including a signal apparatus, a tuned circuit for controlling the supply of high frequency currents to said signal apparatus

and means responsive to the current flowing in said anode circuit for controlling said tuned circuit.

16. The combination in a signaling system of a transmitting circuit including an electron discharge oscillation generator having an anode circuit, a receiving circuit, means

for controlling a characteristic of said receiving circuit, and means responsive to current flowing in said anode circuit for controlling said first means.

In witness whereof, I have hereunto set my hand this 13th day of January, 1927.

EMMETT F. CARTER.
